Primary Examiner — Karen S Acker(74) *Attorney, Agent, or Firm* — Barry Choobin; Patent 360(57) **CLAIM**

The ornamental design for a paper tissue, as shown and described.

DESCRIPTION

FIG. 1 is a perspective view of a paper tissue, showing my new design;

FIG. 2 is a front view thereof;

FIG. 3 is a back view thereof;

FIG. 4 is a top view thereof;

FIG. 5 is a bottom view thereof;

FIG. 6 is a right-side view thereof;

FIG. 7 is a left-side view thereof; and,

FIG. 8 is a perspective view of the paper tissue of FIG. 1 shown in a position of use with an unclaimed stack of paper tissues.

The broken lines depict environmental subject matter that forms no part of the claimed design.

1 Claim, 7 Drawing Sheets(56)
